Filed Apr. 30, 1968, Ser. No. 11,720

Term of patent 14 years

Int. Cl. D22—06
U.S. Cl. D22—27

FIG. 1 is a perspective view of a bait casting reel embodying our new design;

FIG. 2 is a perspective view taken from the end opposite that shown in FIG. 1; and,

FIG. 3 is a top plan.

The characteristic features of our design reside in the striated thumb slide antireverse control atop one side plate and a relatively large, contoured backlash control on the face of the opposite side plate in combination with a fishing reel, all as shown.

We claim:

The ornamental design for a bait casting reel, as shown and described.
